LOOM SHUTTLE

John J. Kaufmann, Jr., Greenville, S. C., assignor
to Steel Heddle Manufacturing Company,
Philadelphia, Pa., a corporation of Pennsylvania

Application November 10, 1949, Serial No. 126,480

5 Claims. (Cl. 139—207)

1

This invention relates to loom shuttles, and it relates more particularly to a practical means for adjusting the bobbin gripping devices for the purpose of correcting axial alignment of the bobbin in its relation to the threading block usually provided at the other end of the shuttle.

In the shuttles used in automatic looms, and particularly those of the weft replenishing type, the permanently located spring gripping jaws which engage the rings at the butt end of the bobbin often become worn in use, due to the rough usage at the time of the exchange of the bobbins in the shuttle, with the result that the front end of the bobbin will often require adjustment in the vertical plane so that the filling yarn running off from the bobbin will be fed properly to the threading block which is mounted at the other end of the shuttle from that in which the bobbin gripping device is located. Heretofore such adjustment could only be made by disassembling the entire gripping device and refitting the same in the shuttle.

The principal object of the present invention is to provide, in a shuttle of the weft replenishing type, a practical means for readily and easily adjusting the gripping mechanism without dismantling the same so that the free end of the bobbin may be brought to the proper location whereby the filling yarn will be fed properly from the bobbin to the threading block.

A further object of the present invention is to provide, in a loom shuttle, a device of the character aforesaid, which may be inexpensively made, and which will be simple yet efficient in its action.

The nature and characteristic features of the present invention will be more readily understood from the following description, taken in connection with the accompanying drawing forming part hereof, in which:

Figure 1 is a view, partly in section and partly in elevation, of one end of a loom shuttle provided with a bobbin gripping device embodying the main features of the present invention;

Fig. 2 is an underneath plan view of the arrangement shown in Fig. 1;

Fig. 3 is a view similar to Fig. 1, showing a modified form of the invention;

Fig. 4 is an underneath plan view of the arrangement shown in Fig. 3; and

Fig. 5 is an enlarged detail view illustrating certain portions of the device shown in Figs. 3 and 4, the same comprising a section taken on the line 5—5 of Fig. 3.

It should, of course, be understood that the description and drawing herein are illustrative

2

merely, and that various modifications and changes may be made in the structures disclosed without departing from the spirit of the invention.

5 Referring to the drawing, as there shown, the shuttle comprises the usual shuttle body 10, having a central chamber 11 therein in which is located the bobbin 12 which carries the filling yarn laid into the cloth by the shuttle.

10 The thread delivery end of the shuttle (not shown) and the threading device mounted therein may be of any preferred construction.

The end of the shuttle shown is provided with a bobbin gripper spring 13 for releasably holding the butt portion 14 of the bobbin 12.

15 The gripper spring 13 may be of any of the ordinary shapes commonly used, having a U-shaped shank portion 15 which may be anchored in the body portion of the shuttle by 20 means of a transverse bolt 16 or in any other preferred manner.

The shank end 15 of the gripper spring 13 is also secured by means of a grip strap 19 comprising a bottom horizontal portion 20 which is 25 located in the base of the groove or recess 21 provided in the end of the shuttle body and is engaged by the lower face of the gripper spring 13.

20 The grip strap 19 is also provided with a top portion 22, the under face of which engages and grips 25 the top face of shank portion 15 of the gripper spring 13 and having the usual inclined portion 23, at the end toward the shuttle cavity, for guiding the butt 14 of the bobbin 12 to the proper position within the shuttle so that the rings 17, 30 usually provided on the butt end 14 of the bobbin 12 will be gripped by the grooves 18 provided in the jaws of the gripper spring 13.

35 In the form of the invention shown in Figs. 1 and 2 of the drawing, portions of the bottom portion 20 of the grip strap 19 are punched inwardly as at 24 and threaded whereby the same may be engaged by the threaded portion 25 of an adjusting screw 30 which is mounted therein.

The adjusting screw 30 also has an enlarged 40 head portion 26 which is seated in the base of a groove or recess located below the inner end of the lower portion 20 of the grip strap.

45 The grip strap 19 is also secured in place by means of a vertically mounted bolt 27, located 50 adjacent the transverse bolt 16 which serves to anchor the gripper spring 13 against longitudinal movement in the shuttle body 10.

The adjusting screw 30 also has, internally arranged, a non-circular cavity 28 adapted to 55 be engaged by a complementally shaped wrench

(not shown) and for the purpose of permitting access to said cavity 28 by the wrench, the part of the body portion of the shuttle, which is disposed below the adjusting screw, is provided with an aperture 29 through which the wrench may be inserted.

The manner of use of the invention as above described is as follows:

If either initially, or, in the course of time, it is found that the axis of the bobbin 12 is out of alignment with the threading block (not shown) in the other end of the shuttle, it is only necessary for the purpose of adjusting the same, to insert the wrench through the aperture 29 into the cavity 28 of the adjusting screw 30 and to turn the same in the proper direction, whereby the grip strap 19 and consequently the gripper spring 13 will be given a slight angular movement, substantially about the axis provided by the transverse bolt 16 which passes through the shank portion 15 thereof.

It has been found in practice that a very small amount of adjustment is necessary, in the device of the present invention, by reason of the fact that the angular shifting of the gripper spring 13 is greatly magnified by reason of the relatively greater length of the bobbin 14.

The device shown in Figs. 3 and 4 is substantially similar to that shown in Figs. 1 and 2 with the exception that, in lieu of the struck-in portions of the base part of the grip strap 19 being bent in and threaded as above described for the mounting of the adjusting screw, the base portion 20 of the grip strap is provided with a non-circular aperture 31 in which a nut 32, having its exterior complementally shaped with respect to the aperture, is provided for the mounting of the adjusting screw 30 therein. The nut 32 may have a head portion 33 bearing against the under face of the bottom portion 20 of the grip strap.

The operation of the device shown in Figs. 3, 4 and 5 of the drawing is, of course, the same as that shown in Figs. 1 and 2.

I claim:

1. In a loom shuttle of the weft replenishing type having a bobbin gripper spring mounted therein with a shank portion secured in a recess in the body of the shuttle, a grip strap having top and bottom portions engaging the shank portion of the gripper spring, an adjusting screw mounted in the bottom portion of the grip strap, said adjusting screw adapted, when adjusted, to angularly shift the gripper spring thereby to shift the axis of the bobbin in its vertical plane.

2. In a loom shuttle of the weft replenishing

type having a bobbin gripper spring mounted therein with a shank portion secured in a recess in the body of the shuttle, a grip strap having top and bottom portions engaging the shank portion of the gripper spring, an adjusting screw mounted in the bottom portion of the grip strap, said adjusting screw having a head portion bearing against a portion of the shuttle body and adapted, when adjusted, to angularly shift the gripper spring thereby to shift the axis of the bobbin in its vertical plane.

3. In a loom shuttle of the weft replenishing type having a bobbin gripper spring mounted therein with a shank portion secured in a recess in the body of the shuttle, a grip strap having top and bottom portions engaging the shank portion of the gripper spring, an adjusting screw threaded in a struck in part of the bottom portion of the grip strap, said adjusting screw adapted, when adjusted, to angularly shift the gripper spring thereby to shift the axis of the bobbin in its vertical plane.

4. In a loom shuttle of the weft replenishing type having a bobbin gripper spring mounted therein with a shank portion secured in a recess in the body of the shuttle, a grip strap having top and bottom portions engaging the shank portion of the gripper spring, a nut mounted in the bottom portion of the grip strap, an adjusting screw threaded in said nut, said adjusting screw adapted, when adjusted, to angularly shift the gripper spring thereby to shift the axis of the bobbin in its vertical plane.

5. In a loom shuttle of the weft replenishing type having a bobbin gripper spring mounted therein with a shank portion secured in a recess in the body of the shuttle, a grip strap having top and bottom portions engaging the shank portion of the gripper spring, a nut mounted in the bottom portion of the grip strap, an adjusting screw threaded in said nut, said adjusting screw having a head portion bearing against a portion of the shuttle body and adapted, when adjusted, to angularly shift the gripper spring thereby to shift the axis of the bobbin in its vertical plane.
